UNITED STATES PATENT OFFICE.

ROBERT CARL RAHM, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-MACHINE.

1,182,037.

Specification of Letters Patent.

Patented May 9, 1916.

Application filed August 3, 1915. Serial No. 42,419.

To all whom it may concern:

Be it known that I, ROBERT CARL RAHM, a citizen of the United States, residing at Wyomissing, in the county of Berks and State of Pennsylvania, have invented certain new and useful Improvements in Braiding-Machines, of which the following is a specification.

My invention relates particularly to the ordinary type of braiding machine having a series of equally spaced intersecting race-circles and carrier drive gears; and my object is to adapt such machines for use as stripe braiders by enabling the carriers to be conveniently operated on determined sections of the course so as to interloop certain only of the threads, the invention consisting in arranging three adjoining race-circles of the course to serve as terminals for such purpose, as hereinafter fully described in connection with the accompanying drawings and specifically pointed out in the claims.

Figure 1 shows a portion of a form of striped braid, of specifically novel structure, which my improved machine is adapted to produce, the same being enlarged to clearly indicate the lay of the threads as affected by the setting-back and reversal of the carriers. Fig. 2 is a plan view of a portion of a machine embodying my invention; the switches and braiding carriers being shown in positions illustrating the operation in producing said striped braid.

As shown in Fig. 2, the intersecting race-circles 1, 2, 3, 4, 5, 6, 7 in the top plate 10 of the machine, which form a part of a complete carrier race-way, are equally spaced as in an ordinary plain braider; and at the centers of these race-circles are mounted an intermeshing series of carrier drive gears having equal pitch circles 11 and each provided with a carrier operating disk adapted for four engaging wings or horns as usual.

When all of the operating disks of these gears are provided with the usual four horns, the carriers, which may be reversed upon end terminals (not shown) as usual, will be continuously passed through the several race-circle sections to form a plain braid. In my improved construction however three adjoining intermediate race-circle sections 3, 4 and 5, are arranged to serve as striping terminals, as determined by suitably operated reciprocating switches 12 and

13 located as shown between the middle race-circle terminal 4 and the adjoining race-circles 3 and 5 respectively.

The middle terminal 4 has the carrier engaging disk of its drive-gear provided with only two oppositely arranged horns, the other two being removed; so that any carrier entering said terminal from either direction will be set back one horn.

Each of the adjoining terminals, 3 and 5, has its drive gear disk provided with two ordinary horns and two elongated ones, 14 and 15, alternately arranged; and each has its race-circle provided with an eccentric extension 16; which known arrangement is provided for setting back carriers which are brought onto said eccentric extensions by the short horns, said carriers being compelled to await engagement by the succeeding long horn.

The eccentric extensions 16 of the race-circles 3 and 5, are at opposite sides of the latter, and adjacent the respective switches 12 and 13. The middle race-circle 4 serves as a common terminal for carriers entering it from the right or left, as determined by the set of the switches 12 and 13; while the adjoining race-circles 3 and 5 serve as terminals for the carriers from the left and right respectively, which are retained on such circles by said switches. So that by proper operation of the latter certain of the carriers may be passed through the side terminals, 3 or 5, to the common middle terminal 4, and the threads thereof interlooped on the latter as indicated at 20 Fig. 1; while others may be reversed upon the side terminals 3 and 5 respectively so as to form stripes 21, 21'; all of the carriers being properly set back upon the several terminals 3, 4 and 5, by the conjoint use of the two-horn common terminal 4 and the long-and-short horned adjoining terminals 3 and 5, so as to prevent any interference of the passing and reversing carriers.

It will be understood that my improved construction not only provides for the making of stripe braids as described, but enables the convenient utilizing of the machine for the making of plain braids, by merely restoring the omitted horns on the carrier drive gear of race-circle 4, and turning the drive gear of either 3 or 5, a quarter turn; for all the carriers entering on circles 3 or 5, from opposite directions, so as to traverse

the eccentric extension 16 of said circles, will then be engaged by the long horns so as to be continued on their course uninterrupted notwithstanding the eccentric extensions, so that all of the three circles 3, 4 and 5 which served as terminals in the previously described operation, would serve the same as ordinary race-circles in plain braiding.

10 What I claim is:

1. A stripe braider having a carrier course comprising a series of three intersecting race-circle sections all of which are provided with carrier drive-gears of equal pitch diameters; an intermediate one of said three sections being provided with means for setting-back carriers entering it in either direction, and the adjoining sections being provided with means for setting-back carriers 15 entering them respectively from the right

and the left; reciprocating switches being provided between said intermediate section and each adjoining section.

2. A stripe braider having a carrier course comprising a series of three equally spaced intersecting race-circles each of which is provided with a four-horn carrier drive gear and is adapted to serve as a terminal; the drive-gear of the middle one of said terminals having opposite horns removed so as to set-back carriers entering said terminal in either direction, and each of the adjoining terminals having a drive-gear provided with opposite elongated horns and a race-circle having a lateral extension; reciprocating switches being provided between said middle terminal and the adjoining terminals. 25 30 35

In testimony whereof I affix my signature.

ROBERT CARL RAHM.
